[57] CLAIM

We claim the ornamental design for a patient controlled analgesia actuator, as shown and described.

DESCRIPTION

FIG. 1 is a perspective view of said patient controlled analgesia actuator displaying our design;

FIG. 2 is a top plan view of the actuator;

FIG. 3 is a bottom plan view of the actuator;

FIG. 4 is a left side elevational view of the actuator;

FIG. 5 is a right side elevational view of the actuator;

FIG. 6 is a rear elevational view of the actuator; and,

FIG. 7 is a front elevational view of the actuator.
